(57) **CLAIM**

The ornamental design for a brush, as shown and described.

DESCRIPTION

FIG. 1 is a first top perspective view of a brush in accordance with the present invention;

FIG. 2 is a right side view of the brush of FIG. 1;

FIG. 3 is a left side view of the brush of FIG. 1;

FIG. 4 is a rear view of the brush of FIG. 1;

FIG. 5 is a front view of the brush of FIG. 1;

FIG. 6 is a top view of the brush of FIG. 1;

FIG. 7 is a bottom view of the brush of FIG. 1;

FIG. 8 is a second top perspective view of the brush of FIG. 1;

FIG. 9 is a first bottom perspective view of the brush of FIG. 1; and,

FIG. 10 is a second bottom perspective view of the brush of FIG. 1.

The broken lines of FIGS. 1-10 illustrate portions of the brush that form no part of the claimed design.

1 Claim, 10 Drawing Sheets
